UNITED STATES PATENT OFFICE.

HERMANN KESTNER, OF MÜLHAUSEN, GERMANY.

METHOD OF EMBEDDING THIN PRINTED LABELS MADE OF GELATIN IN TRANSPARENT SOAP.

1,114,006.

Specification of Letters Patent.

Patented Oct. 20, 1914.

Application filed November 26, 1913. Serial No. 803,359.

To all whom it may concern:

Be it known that I, HERMANN KESTNER, a subject of the Emperor of Germany, residing at Mülhausen-in-Alsace, Germany, 5 have invented a new and useful Improved Method of Embedding Thin Printed Labels Made of Gelatin in Transparent Soap, of which the following is a specification.

This invention has reference to an improved method of embedding thin printed labels made of gelatin in cakes or bars of transparent soap.

The method heretofore followed in embedding thin printed gelatin labels in transparent soap has been to take two pieces of soap, to place the label flat upon one piece, and then to press the two pieces together with the label between them. Sometimes a suitable adhesive is employed to assist in securing the label in position. It is however impossible to insure by pressing or by the use of an adhesive that the two parts of the cake or the like will remain securely attached to each other. An adhesive that 25 will meet all the requirements for permanently securing one piece of soap to another is almost inconceivable, and pressure alone does not insure the adhesion of two pieces of soap which are in a compressible state 30 *i. e.* partially dried. The two parts of the cake separate or slide upon each other more or less readily when the cake is being used, and air bubbles are often left between the pieces, thereby giving the cake an unsightly 35 appearance and prejudicially affecting the adhesion between the two pieces. When in use, the water finds its way from all sides into the joint between the pieces, destroying the label and quickly and surely bringing 40 about the separation of the two parts.

It has been proposed to introduce labels into cakes of soap by making a slit in the soap with a knife and then inserting, by hand and without employing any auxiliary 45 means, a label into the slit and subjecting the cake to pressure in a flat press. This method can only be followed if stiff and comparatively rigid labels which will stand handling and are not easily broken or bent 50 are employed, and such labels are necessarily non-transparent or must be made of glass, celluloid, mica or the like. They cannot be made of extremely thin films of gelatin. That method has therefore serious defects. The stiff labels project from the soap

at their edges when the cake has been in use for some time, and injury to the hands or other parts of the body is likely to result from contact with the sharp edges of the label. At the least, the projecting edges 60 of the label make the cake unsightly and it is therefore not marketable as an advertising article, the cake being thrown on one side as soon as the edges of the stiff insertion begin to project from the soap. 65

The object of the present invention is the production of transparent pieces of soap with extremely thin and perfectly transparent printed labels embedded therein, the film-like labels being quite invisible in the 70 soap. The gelatin films which I employ are the extremely thin sheets of gelatin which are known commercially as No. 00. My invention obviates the defects indicated above as the thin gelatin labels become practically 75 embodied in the soap by absorbing moisture therefrom and being to a certain extent dissolved in the soap so that the edges of the label always wear away regularly with the soap and never project therefrom and consequently can never cause any injury to the 80 body or cause the cake of soap to become unsightly. Further the soap can be used up to the last particle.

The cake of soap is formed with a sheath-like slit by pushing into the body of the cake from one side a flat chisel-like knife formed with a cutting edge at its front end and also on both sides. An ordinary planing machine may be employed for pushing 90 in the knife.

The invention is illustrated in the accompanying drawing, in which:—

Figure 1 is a plan view and Fig. 2 a longitudinal section of a cake of soap *a* 95 with a knife *b* pushed thereinto to form the sheath-like slit. Fig. 3 is a cross-section of the knife, and Fig. 4 shows the stiff strips of paper which are employed for inserting the film-like label into the slit formed in 100 the soap.

The width of the knife *b* is usually about an inch less than the width of the cake of soap, and the said knife is pushed into the soap until its front cutting edge is about 105 half an inch from the outer edge of the cake. When the knife has been withdrawn from the soap, the label is introduced into the slit, and my invention consists essentially in the particular method and manner 110

of introducing and embedding an extremely thin gelatin label in the slit. This could not be done without employing auxiliary means on account of the insufficient rigidity of the 5 extremely thin film of gelatin, which is very easily bent or broken or caused to roll up.

For the purpose of introducing the label into the slit, the said label is placed between 10 two stiff strips of paper *c* as shown in Fig. 4, in which the position of the label between the said strip is indicated in dotted lines. Thereupon the two strips of paper with the label lying between them are 15 pushed into the slit until they contact with the end of the slit. Then one of the two strips is drawn out of the slit leaving the label in position upon the other strip. Care must be taken of course that in drawing out 20 the first strip from the slit that the gelatin film is not displaced. For this purpose the other strip has formed in it, where indicated by the hatching in Fig. 4, a large number of pin-pricks which form a rough surface on 25 that side of the strip with which the gelatin film is in contact. Each pin-prick produces a small and almost invisible round projection in the paper. If the film has a tendency to become displaced when the first 30 strip of paper is being withdrawn, the edge *d* of the label can immediately find many resistance points in the pin-prick projections and be prevented from sliding outward. When the first strip has been with- 35 drawn the gelatin film comes into direct contact with the soap and adheres thereto so that removal of the second strip of paper is never accompanied by any displacement of the label.

40 After the two strips of paper have been withdrawn, the cake of soap is passed between rollers, the solid edge of the cake (*i. e.* the left hand edge of the cake shown in the drawings) being first pushed between

the rollers so that as the cake passes between 45 the rollers the sides of the slit are pressed together and the air is pressed out of the slit, all trace of the slit being obliterated and not even the smallest air bubble being left in the soap. 50

What I claim as my invention and desire to secure by Letters Patent is:—

1. A method of embedding thin printed labels made of gelatin in cakes of transparent soap, consisting in forming in the body 55 of the cake a sheath-shaped slit to receive the label, placing the thin gelatin label between two strips of stiff paper, inserting the said strips with the label between them into the aforesaid slit, withdrawing first 60 one and then the other of the said strips, and then passing the cake between pressing rollers to close the slit and force the air out of same.

2. A method of embedding thin printed 65 labels made of gelatin in cakes of transparent soap, consisting in forming in the body of the cake a sheath-shaped slit to receive the label by means of a chisel-like blade formed with cutting edges at each side and 70 also at its front end, placing the thin gelatin label between two stiff strips of paper which are slightly wider than the label and in one of which a number of pin-pricks are 75 formed to prevent displacement of the label thereon, inserting the said strips with the label between them into the aforesaid slit, withdrawing first one and then the other of the said strips, and then passing the cake between pressing rollers to close the slit 80 and force the air out of same.

In testimony whereof I have signed my name to this specification in the presence of two subscribing witnesses.

H. KESTNER.
